UNITED STATES PATENT OFFICE.

LORIN C. FORWOOD, OF LINCOLN, ILLINOIS.

APPARATUS FOR GRINDING AND POLISHING METALS.

SPECIFICATION forming part of Letters Patent No. 716,403, dated December 23, 1902.

Application filed October 14, 1901, Serial No. 78,553. (No model.)

To all whom it may concern:

Be it known that I, LORIN C. FORWOOD, a citizen of the United States, residing at Lincoln, in the county of Logan and State of Illinois, have invented certain new and useful Improvements in Apparatus for Grinding and Polishing Metals, of which the following is a specification.

My invention relates to apparatus for grinding and polishing metals by means of a sand-blast.

The general purpose of my invention is to provide an apparatus so constructed and arranged that air-pressure of different degrees may be employed during the operation of grinding or polishing; and with this general purpose in view the more specific purposes of my invention are to provide an air-reservoir having compartments adapted to contain air under different degrees of pressure, the pressure in any one of the compartments being subject to control without affecting the pressure in the other compartments; to provide a sand-receptacle of novel and improved form; to provide a mixing-valve of improved construction; to provide a valve of improved construction for controlling the discharge of sand through a nozzle; to provide a nozzle of novel and improved form; to provide means for automatically operating the nozzle-valve; to provide a reducing-valve of novel and improved construction, and to provide means for removing from the sand the particles of metal abraded from the article operated upon.

With these ends in view my invention consists in the novel features of construction and combinations of parts shown in the annexed drawings, to which reference is hereby made and hereinafter particularly described, and 40 finally recited in the claims.

Referring to the drawings, Figure 1 is a perspective view of the main structure. Fig. 2 is an enlarged sectional view of one of the reducing-valves. Fig. 3 is an enlarged side elevation of the nozzle and connected parts. Fig. 4 is an enlarged top plan of the nozzle and nozzle-valve. Fig. 5 is a vertical longitudinal section on the line 5 5 of Fig. 4. Fig. 6 is a horizontal longitudinal section on the line 6 6 of Fig. 3. Fig. 7 is an enlarged end elevation of a modified form of the apparatus. Fig. 8 is a horizontal section on the

line 8 8 of Fig. 7. Fig. 9 is a vertical section through the cradle on the line 9 9 of Fig. 8. Fig. 10 is a transverse vertical section on the line 10 10 of Fig. 8. Fig. 11 is an enlarged side elevation of the modified form of valve shown in Fig. 7. Fig. 12 is an enlarged sectional view of the mixing-valve.

Similar reference-letters designate like parts in all of the views.

I have shown in the drawings and will hereinafter describe my invention as applied in the grinding and polishing of plows; but it may with equal advantage and without material modification be employed in the cutting, grinding, or polishing of other articles.

The air-reservoir A consists of a rectangular box divided into compartments by transverse partitions α' . An air-supply pipe B, connected with any suitable source of air-supply, is connected with the compartments in the reservoir A by reducing-valves D, opening into the compartments, respectively. A sand-box E is supported on the reservoir A by standards α . The upper end of the box E is open, and transverse bars e' fit in mortises e^2 in the upper edges of the box and are movable, so that they may be placed in convenient position for the work in hand. A partition e extends lengthwise above the box. A hood F is supported above the box E by rods f' , connected with any suitable support. Exhaust-pipes f serve to convey away the dust formed during the operation of grinding or polishing. An air-pipe b opens into each of the compartments of the reservoir A, and the upper end of the pipe is connected with the mixing-valve K. A sand-pipe k is connected with the sand-box E, and the upper end of the pipe is connected with the valve K. A hose N (not shown) connects the valve K with the nozzle-valve G. The nozzle-base H is suitably secured to the valve G, and nozzle-plates H' are detachably connected with the base H. A lever G^2 controls the supply of mixed sand and air passing through the nozzle. The reducing-valve D screws into a reinforcing-plate D^4 , secured on the inside of the reservoir A. A plug D' may be turned so as to open or close the valve. Within the valve D is a plug D^2 , which seats on a conical seat d within the valve and has an upwardly-extending stem d' . A coiled spring D^3 surrounds

the stem d' and acts against a washer d^3 on the stem to lift the plug. Nuts d^2 screw on the stem d' , and the tension of the spring D^3 may be adjusted by turning the nuts up or down, 5 as occasion may require. The valve D is connected with the pipe B by any suitable connection, and air passes from the pipe through the valve into the reservoir. The air-pressure maintained in the main supply-pipe B is all 10 ways in excess of the greatest pressure required in any compartment of the air-reservoir. The pressure of air within each compartment of the reservoir is controlled by adjusting the plug D^2 to operate at the required 15 pressure. For example, if it is desired to maintain in one compartment a pressure of sixty pounds, in another a pressure of forty pounds, and in another a pressure of twenty pounds the springs D^3 of the valves opening 20 into the compartments, respectively, will be adjusted by means of the nuts d^2 , so that the spring will react to close the valve when the pressure in one compartment exceeds sixty pounds, to close the valve in another compartment when the pressure exceeds forty 25 pounds, and to close the valve opening into another compartment when the pressure exceeds twenty pounds.

It will be seen then that variable degrees 30 of pressure may be maintained within the respective compartments, or the same pressure may be maintained within all of the compartments. The nozzle and its connections are preferably mounted on a frame J , which 35 has a handle J' , by means of which the frame and its connections may be manipulated.

In practical use the frame J is placed on top of the article to be operated upon, and the nozzle being set at the proper angle the frame 40 is moved to and fro, so as to subject to the action of the sand-blast the entire surface to be operated upon. A bracket J^2 extends upwardly from the handle J' , and a trunnion g on the valve G fits and turns in a hole in the 45 upper end of the bracket. A plug G' , pierced by a hole g' , turns in the valve-body and has a stem g^2 projecting through the valve-body. A lever G^2 is secured to the stem g^2 . A spring G^3 , surrounding the valve-stem, is compressed 50 when the handle G^2 is turned to open the valve and reacts to close the valve. The nozzle-base H is secured to the valve G by a coupling G^4 and has an integral extension h , on which the nozzle-plates H' are supported. 55 The clamp H^2 surrounds the plates H' and the extension h and clamps the plates on the extension. The clamp H^2 consists of two members h^2 , joined by a hinge h^3 . A bolt h^4 passes through the upper member h^2 and 60 screws into the lower member h^2 . By turning the bolt the members may be drawn together, so as to clamp the plates, as above set forth.

The mixing-valve K has two members k' 65 and k^2 , joined by a union k^3 . The air-pipe b screws into the member k' , and the sand-pipe

k screws into the member k^2 . A cock k^9 turns in the member k' and has a stem k^7 , passing through a plug k^6 and having at its outer end a hand-wheel k^5 , by which the valve may 70 be operated. A pin k^{11} holds the plug k^6 in place. A nozzle k^4 screws into the end of the union k^3 and passes through the member k^2 into a pipe k^8 , which screws into the member k^2 . The cock k^9 has a way k^{10} , through which 75 air is admitted into the valve.

The operation of the valve is as follows: The cock k^9 is turned so as to admit air through the part k' and through the nozzle k^4 . The air escaping through the nozzle produces a vacuum in the chamber of the part k^2 , which causes sand to rise through the pipe k and pass into the pipe k^8 , whence it is driven forward by the air-pressure behind it. 80

In the preferable form of my apparatus I 85 employ the nozzle and attachments shown in Figs. 3, 4, 5, and 6 of the drawings.

With slight modifications, which I will now describe, the nozzle-valve may be adapted to 90 operate automatically.

In the modified form of my apparatus I employ a cradle M , one end of which is connected with a rope m or equivalent supporting device, so that the cradle may swing freely. Handles m' serve to manipulate the cradle. 95 The bottom of the cradle is slotted or perforated, and beneath the slotted bottom is a box adapted to contain sand. A hood m^2 curves upwardly from the inner end of the cradle and prevents the sand from being blown out 100 of the cradle at the end, and side boards m^3 prevent sand from being blown sidewise from the cradle. The nozzle and attachments employed with the cradle are the same as those already described, except that the extremity 105 of the nozzle is turned downward, as shown in Fig. 11, and other slight modifications in the means for operating the lever G^2 , as hereinafter set forth. On one side of the valve G are eyes g^3 , in which a rod g^4 slides. A little 110 roller g^5 is mounted to turn in the lower end of the rod g^4 . A rod g^6 connects the rod g^4 with the lever G^2 , and the lever G^2 is connected with the valve-stem g^2 in such manner that when the rod g^4 is raised it will raise 115 the lever G^2 , so as to open the valve, and when the rod descends the valve will close automatically. In the practical use of this modified form of the apparatus the article to be operated upon is placed in the cradle in 120 such position that when the cradle is raised the roller g^5 will engage with the surface to be operated upon, and the quantity of sand to be employed in operating upon the article may be effectively controlled by raising or 125 lowering the cradle, so as to open or close the valve to such extent as may be most advantageous for the operation in hand. Under the hood m^2 is a transverse rod m^4 , upon which is supported a series of horseshoe-magnets m^5 . The magnets m^5 serve to attract particles of metal in the sand and prevent them 130

from falling down into the sand-box. This feature is of practical advantage, because it is desirable to separate the metallic particles from the sand, for the reason that any considerable accumulation of the metal in the sand impairs the cutting quality of the sand. The magnets m^5 may be removed for cleansing by withdrawing the rod m^4 .

The operation of the apparatus is as follows: The article to be operated upon is placed on the table E. The valve D is then adjusted to give the desired air-pressure in the compartment of the reservoir from which the air is to be taken. The valve K is then opened to admit sand and air into the mixing-valve. The operator then takes the handle J' in his hand and places the frame J in position to operate on the article. He then seizes the lever G² with the same hand that holds the handle J' and draws the lever toward the handle, so as to open the valve. He then moves the frame J to and fro over the surface to be operated upon and by opening the valve to a greater or less extent controls the supply of sand acting on the surface.

The operation of the modified form shown in Figs. 7 and 8 is the same, except that the article to be operated upon is placed on the cradle, and the cradle is manipulated to control the flow of sand through the nozzle, as already explained.

Having fully described my invention, what I claim as new, and desire to secure by Letters Patent, is—

35 1. In an apparatus of the class described, the combination of an air-reservoir, an air-pipe connected with a source of air-supply, a reducing-valve connecting said pipe with said reservoir, a sand-box contiguous to said reservoir, a mixing-valve contiguous to said sand-box, pipes connecting said mixing-valve with said reservoir and said sand-box, a nozzle-valve in connection with said mixing-valve

and a nozzle in connection with said nozzle-valve as set forth.

2. In a reducing-valve, the combination of a body portion D, a plug D' and a plug D², seated in said body portion and having a stem d, a washer d³ on said stem, and a spring D³ acting against said washer, as set forth.

3. In an apparatus of the class described, the combination of a frame J, a handle J' and a bracket J², with a valve having a trunnion turning in said bracket and a lever for operating said valve by the same hand that holds the handle, as set forth.

4. A mixing-valve, for apparatus of the class described, consisting of members k' and k² connected by a union, a nozzle connected to said union within the member k² and a pipe 60 connected with the member k², in combination with an air-reservoir, a pipe connecting said reservoir with said member k', a sand-box, and a pipe connecting said sand-box with said member k², as set forth.

5. In a mixing-valve for an apparatus of the class described the combination of members k' and k², a union joining said members, a nozzle screwing into said union, a cock turning in the member k', a plug fitting in the 70 member k' and means for securing said plug, as set forth.

6. In an apparatus of the class described, the combination of a frame J, handle J', a bracket J², a valve-body having a trunnion 75 turning in said bracket, a plug fitting in said valve-body, a lever adapted to turn said plug to open the valve and a spring reacting to turn the plug to close the valve, as set forth.

In witness whereof I have hereunto subscribed my name, at Lincoln, Illinois, this 14th day of August, 1901.

LORIN C. FORWOOD.
